Geo. F. Meacham

UNITED STATES PATENT OFFICE.

GEORGE F. MEACHAM, OF NEWTON, ASSIGNOR TO JAMES W. TUFTS, OF MEDFORD, MASSACHUSETTS.

DESIGN FOR THE CASING OF A SODA-WATER APPARATUS.

Specification forming part of Design No. 7,140, dated January 27, 1874; application filed December 15, 1873.
[Term of Patent 14 years.]

B.

To all whom it may concern:

Be it known that I, GEORGE F. MEACHAM, of Newton, in the county of Middlesex and State of Massachusetts, have invented and produced a new and original Design for the Casing of a Soda-Water Apparatus, of which the following is a full, clear, and exact description, reference being had to the accompanying photograph making part of this specification.

In the photograph, A represents the base, of rectangular form, upon which rests the body or main portion B of the casing, each end of which is beveled or inclined inward from a to the beading b, above which is a cornice, c, which extends up to the under side of the flat rectangular top or cap D, from the center of which projects a pedestal, E, for supporting a vase, statue, or other ornament, the design thus produced being unique and ornamental. At each corner of the top D is secured or cast

an image, d, of a sphinx, as shown, and at or near the center of the front of the casing is an ornament, e, representing the "winged globe"—an Egyptian symbol.

What I claim as my invention, and desire to secure by Letters Patent, is—

1. The design for the casing of a soda-water apparatus, substantially as herein shown and described.

2. The sphinxes d on the top D, substantially as shown and described.

3. The "winged globe" e, applied to the casing of a soda-water apparatus, substantially as shown and described.

Witness my hand this 10th day of December, A. D. 1873.

GEO. F. MEACHAM.

In presence of—

P. E. TESCHEMACHER,
G. A. MEACHAM.
